(57) **CLAIM**

The ornamental design for a camcorder, as shown and described.

DESCRIPTION

FIG. 1 is a front and right side perspective view of a camcorder showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is bottom plan view thereof.

The broken lines in the drawings are shown to illustrate portions of a camcorder in which the design is embodied and form no part of the claimed design.
